Primary Examiner — Elizabeth J Oswecki*(74) Attorney, Agent, or Firm* — Hess Patent Law Firm LLC; Robert J. Hess**CLAIM**

An ornamental design for an electrode cap, as shown and described.

DESCRIPTION

FIG. 1 is a front, right side, top isometric view of an electrode cap showing our new design;

FIG. 2 is a right side elevation view thereof;

FIG. 3 is a front elevation view thereof;

FIG. 4 is a left side elevation view thereof;

FIG. 5 is a rear elevation view thereof;

FIG. 6 is a top plan view thereof; and,

FIG. 7 is a bottom, rear isometric view thereof.

The broken lines shown in the drawings represent portions of the electrode cap that form no part of the claimed design.
